UNITED STATES PATENT OFFICE.

ERNEST KILBURN SCOTT, OF BELVEDERE, ENGLAND.

ELECTRIC FURNACE FOR FIXING NITROGEN FROM THE AIR.

1,113,376.

Specification of Letters Patent.

Patented Oct. 13, 1914.

Application filed June 25, 1913. Serial No. 775,715.

To all whom it may concern:

Be it known that I, ERNEST KILBURN SCOTT, consulting engineer, of Osborne House, Belvedere, Kent, England, have invented a certain new and useful Improved Electric Furnace for Fixing Nitrogen from the Air, of which the following is a specification.

This invention relates to an electric furnace for the direct fixation of nitrogen from the air. In such furnaces it is important that the gases coming from the arc flame shall be cooled quickly in order to fix the nitric oxide to minimize its disassociation. Further, it is desirable that the temperature shall be still more reduced while the gases are in the immediate proximity of the furnace in order that the nitric oxide may begin to be oxidized into nitrogen peroxid. Previously the usual method of cooling the nitric oxide quickly has been to blow in cold air at the top of the arc flame. This method has had the disadvantage of diluting the fixed gas. According to this invention the furnace chamber is provided with a water-cooled roof forming a steam generator against which directly impinge the arc flames produced between the electrodes which are supplied with current from a polyphase power circuit. If desirable the steam generator may communicate with a superheater, the steam thus raised being employed to drive the machinery which generates the electric power for the furnace. The electrodes preferably are horn-shaped or of other divergent form and radiate from a center above the air inlet, this shape and disposition of the electrodes together with the fact that they are supplied with power from a polyphase circuit results in the formation of an arc flame of substantially conical form as distinct from the flat arc or the long rod-like arc produced in well known forms of nitrogen fixation furnaces.

The electrodes are preferably mounted on carriages and can be advanced into or withdrawn from the furnace chamber, the apertures through which they are introduced being of such a size and shape as to be closed by the electrodes and their carriages when the electrodes are in their operative position.

In the accompanying drawings which illustrate one construction of electric furnace in accordance with this invention,

Figure 1 is a side elevation in vertical section, and Fig. 2 is a plan.

The furnace comprises a fireproof chamber A of circular cross-section in the base of which is a central adjustable air inlet nozzle. The electrodes comprise wedge-shaped blocks of metal C through which cooling water flows by means of pipes C¹, the electrodes being mounted upon insulated carriages D, the wheels D¹ of which preferably run upon rails D². Alternatively, the electrodes may be tubular and curved somewhat similar in shape to lightning arresters of the "horn" type as before being water-cooled and mounted on carriages and having mounted on them suitable projecting members in the form of renewable sleeves or the like if found necessary. The electrodes and their carriages radiate from the central air inlet B, openings A¹ being formed in the lateral walls of the furnace chamber to admit the electrodes and their carriages which together close these openings when the electrodes occupy their operative position. If desired, mechanism may be provided for simultaneously advancing or withdrawing all the electrodes relatively to the furnace chamber.

The roof of the furnace chamber preferably forms a steam generator and in the construction shown in Figs. 1 and 2 comprises an annular chamber E having inclined fire tubes F radiating from a domed central recess E¹, against which impinge the arc flames produced between the electrodes. The steam generator is mounted upon suitable standards or supports G, and is provided with a casing H, in the upper portion of which is formed a flue H¹ through which the gases escape after being cooled by passing through the water-cooled tubes F. In this construction a superheater coil J may be provided above the generator within the chamber H and the steam raised in the generator or additionally heated in the superheater may be employed to drive the machinery which generates the electric power for the furnace.

In the construction illustrated, the electrodes are connected to a three-phase system and the arcs produced between the electrodes form approximately a conical flame (as shown in Fig. 1) when supplied with air from the central inlet B. The central part of the arc flame projects a consider-

able distance above the top of the electrodes, and as the central part of a three-phase arc is at neutral or zero potential, by impinging on the underside of the steam generator 5 the latter is earthed so that no disadvantages arise. The radiating fire tubes E are so arranged that they are always completely surrounded by water and after passing through these tubes and circulating 10 around a superheater coil J, the gases escape through the flue H¹ to the point where they are subsequently treated.

The generator may be so proportioned as to cause the temperature of the gases to be 15 reduced to such an extent that when they enter the flue or discharge conduit this temperature may be approximately that at which the formation of nitrogen peroxid commences.

Having thus described the invention what is claimed as new and desired to be secured 20 by Letters Patent is:

1. In an electric furnace for fixing nitrogen from the air, the combination of a furnace chamber having apertures therein, a 25 plurality of horn-shaped electrodes in said chamber utilizing three-phase alternating current, a carriage for each electrode adapted to be moved into or out of the furnace chamber through said apertures and to close 30

said apertures when occupying their operative positions, an air supply duct arranged centrally within the furnace chamber and a water-cooled roof for the chamber so disposed relatively to the electrodes that the 35 arc flames produced between the electrodes impinge directly against said water-cooled roof which constitutes a steam generator.

2. In an electric furnace for fixing nitrogen from the air, the combination of a furnace chamber, having an air inlet at its lower end, a steam generator comprising a water receptacle forming the top of the furnace chamber and provided with a steam outlet and a gas passage communicating 40 with the furnace chamber and adapted to be surrounded throughout its length by the water in the receptacle, a superheater communicating with the steam outlet of the steam generator and exposed to the gases 45 passing through said gas passage, and electrodes arranged in the furnace chamber.

In testimony whereof I have signed my name to this specification in the presence of two subscribing witnesses.

ERNEST KILBURN SCOTT.
